LATCH OPENING AND WINDOW ACTUATING
MECHANISM

Louis J. Gouin, East Orange, N. J.

Application December 28, 1940, Serial No. 372,023

2 Claims. (Cl. 268—122)

This invention relates to a combination mechanism designed for releasing the latch bolt of a door while also being capable of actuating the window panel arranged in the door to open and close the latter. More particularly the invention relates to a combined control device or mechanism of this kind which is adaptable for use in connection with motor vehicle doors and in which means is provided to retain the latch operating element of the device against movement or operation, said means being manually releasable to facilitate operation of the latch opening element; a further object being to provide a novel lever linkage or coupling between a manually actuated button and the bolt or latch rod for minimizing the pressure upon the button in releasing the latch to open a door; and with these and other objects in view, the invention consists in a device of the class and for the purpose specified, which is simple in construction, efficient in use, and which is constructed as hereinafter more fully described.

The invention is fully disclosed in the following specification, of which the accompanying drawings forms a part, in which the separate parts of my improvement are designated by suitable reference characters in each of the views, and in which:

Fig. 1 is a horizontal sectional view through a device made according to my invention, diagrammatically illustrating its arrangement in a door.

Fig. 2 is a section on the line 2—2 of Fig. 1 taken through the hub portion of the device.

Fig. 3 is a view similar to Fig. 1 illustrating only part of the construction and showing a modification.

Fig. 4 is a sectional view on the line 4—4 of Fig. 3.

The combination latch opening and window actuating device or mechanism herein disclosed, constitutes a continuation of the structure disclosed in my Patent #2,222,659 dated November 26, 1940, in which patent the general adaptation of the invention is illustrated.

It is one of the distinct purposes of my invention to provide not only a finger pressed button in combination with a window operating crank, so that the one device may perform two distinct functions and eliminate the use of independent handles or control devices for the two operations to be performed, but also in providing a further degree of safety in latching or retaining the button against operation without the performance of one additional operation on the part of the op-

erator; namely, to actuate an element releasing the button latch or retaining element to provide free manual operation of said button. The latching and retaining element is automatically returned to normal position upon the release of the applied pressure on said button, and when the latter is returned to normal position.

Further, it is a feature of my invention to arrange the releasing element within the boundaries of the handle member or crank employed for actuating the window, so as to render said element substantially invisible, and further to guard and shield this element against accidental operation to accomplish the ultimate end of positively guarding against accidental opening of a door. A further feature of my invention resides in utilizing a substantially large diameter button for moving the door latch into open position and in minimizing the movement implied thereto as well as in employing an operating lever having sufficient leverage to minimize the pressure applied to the button in unlatching the door.

In the present illustrations, I have eliminated the window mechanism and details of the door structure in order to simplify the illustration, but the coupling and association of the parts will be apparent to those skilled in the art; particularly in view of the more complete disclosure as is illustrated in my patent hereinbefore cited.

In Fig. 1 of the drawing, 10 represents the inner surface of the trim line of a motor vehicle door. 11 shows part of the supporting plate to which is attached a bushing 12 in which is arranged a shaft 13 having at its outer end portion, a gear 14 or other driver for actuating the window of a door in any type and kind of window actuating mechanism. The window is raised and lowered by the rotation of a crank or operating handle 15. The crank 15 has a substantially cup-shaped hub portion 16 having an enlarged flange portion 17 at its open end.

On the bottom wall 18 of the bushing is a thimble-shaped socket part 19, the bore 20 of which is of angular cross sectional form to receive the correspondingly formed shaft 13. The bushing is secured against displacement from the shaft by a screw 21, as clearly illustrated in Fig. 1 of the drawing. The socket 19 includes a flange 22 which projects beyond the bottom wall 18 to form an annular recess on said wall receiving the lower ring 23 of a button frame 24. This frame includes another ring 25 coupled with and spaced from the ring 23 by a plurality of key rods 26. Four of the rods 26 are employed in the construction shown, and these rods pass through

corresponding apertures 27 in the bottom wall 18. One end of the rods 26 is screwed, riveted or otherwise fixedly secured in the ring 25 as seen at 28, and the other ends thereof have a press fit in the ring 23.

At 29 is shown a button which is cup-shaped or thimble-shaped in form and detachably coupled with the ring 25 in any desired manner so as to give access to the interior of the hub 16 in coupling and uncoupling the handle with the shaft 13, as will be apparent. In the construction shown, the button is illustrated as being in screw-threaded engagement with the ring as indicated at 30. The button 29 has a large chamber 31 which fits freely over the socket 19, thus providing free action of the button in the hub portion 16. It will be understood in this connection that the diameter of the button is such as to pass freely into the chamber 32 of the hub 16.

The flange portion 17 of the hub fits over an escutcheon or trimming plate or ring 33. Within the plate 33 is a chamber 34, and in this chamber is mounted a button latching or holding element 35 which is in the form of an elliptical or flattened ring carrying at one side a latch bolt 36, and at an opposed side, an upwardly extending ear 37 in which is secured a small knob 38 which extends inwardly beyond the ear 37 to form a guide and support for a spring 39 which normally urges the element 35 to the right as seen in Fig. 1, to retain the latch 36 in operative position. In this position, the latch extends into a notch 43 formed in one of the posts or key rods 26, as will clearly appear upon a consideration of Fig. 2 of the drawing. The flattened sides 41 of the element 35 fit in notched or recessed portions 42 in the sides of the hub 16 so as to retain the element 35 in proper alignment in the movement of the latch 36 thereof into and out of operative positions. It will appear that the ear 37 extends through and operates in an aperture 43 formed in the escutcheon plate, and by pushing inwardly upon the knob 38, that is to say, in the direction of the axis of the button 29, the element 35 is actuated to withdraw the latch 36 from the recess or notch 43; thus releasing the button to facilitate free inward movement thereof by pressure applied to the outer surface of the button.

At this time, it is well to point out that this operation may be performed by placing a finger of the hand around the handle 15 adjacent the hub portion, and by moving this finger in a direction radially with respect to the hub, and then applying the thumb to the button 29. The two right-angle operations are necessary, however, before the button can be operated. It will be understood that when the button 29 is released and pressure is released from the knob 38, the button will automatically be locked by inward movement of the latch bolt 36 into the recess 43.

Bearing upon the inner surface of the ring 23 are a pair of rollers 44 carried at the free ends of the fork 45 of a lever 46 pivoted as seen at 47 to a suitably supported bracket 48; a spring 49 being employed to aid in supporting the lever in this position. The spring of the latch bolt of the car door, which is coupled with a long link or rod 50, also aids in this operation. The door latch rod 50 has at its inner end a large elliptical portion 51 encircling the bushing 12 and terminating at its inner end in a curved arm 52 which is pivotally coupled to the end 53 of the lever 46, as seen at 54.

It will thus be seen that as the button 29 is manually moved into the hub portion 16, the lever 46 will be swung into the dotted line position indicated in Fig. 1, thus drawing the rod 50 in the direction of the arrow X to retract the latch bolt of the door, facilitating the movement of the door into open position. When the button 29 is released, the lever 46 will automatically return to the full-line position, thus automatically moving the latch bolt of the door into closed or operative position.

From the foregoing, it will appear that there is no positive coupling between the button 29 and the lever 46. Thus, the operation of closing the vehicle door which would impart an inward movement to the latch bolt and also movement to the rod 50 in the direction of the arrow X, will not be transmitted to the button, 29. Moreover, this button is retained against such movement by its retaining element 35 which includes the latch 36.

In the construction shown in Figs. 3 and 4 of the drawing, I have shown a slight modification, which consists in substituting for the element 35 and its associated parts, including the knob 38, a lever 56 which is pivoted within the hollow or recessed portion of the handle or crank 57 as seen at 58, and includes at its inner end a latch retaining element 59 pivotally supported to the pivoted end portion of the lever. The element 59 is similar to the element 36 and extends into the chamber 60 of the hub portion 61 of the handle at a point to engage the upper ring 62 of a frame 63, otherwise identical with respect to the frame 24, except that the recess 40 in one of the rods of the frame has been dispensed with and the rods are located in a different position than that shown in Figs. 1 and 2.

The button 64 is secured to the frame 63 as in Fig. 1, and otherwise the structure in Figs. 3 and 4 is the same as that shown in Figs. 1 and 2; part of the shaft being shown at 65. The lever 56 of the button latch element shown in Fig. 3 is supported in operative position by a coil spring 66 so that the lever extends beyond the inner surface of the handle 57, thus in applying a finger around the handle adjacent the hub 61, the application of pressure will draw the lever 56 into the handle and swing the latch 59 out of engagement with the button frame 63 or the top ring 62 thereof; thus providing free inward movement of the button as will be apparent. When the finger is removed from the lever 56 and pressure is relieved from the button 62, the button will automatically return to latched position as shown in Fig. 3 in the same manner as the return of the button 29 in Fig. 1 of the drawing.

It will appear that in both forms of construction shown, two independent operations are required to move the latch bolt of the vehicle door into inoperative position. In the first instance, that shown in Fig. 1 of the drawing, a radial movement upon the knob 38 is required before applying pressure to the button 29, whereas in Fig. 3, a pinching or gripping action of the hand upon the handle 57 to depress the lever 56 is required before inward pressure can be applied upon the button 64. In connection with the last operation, it will be understood that the pivotal mounting of the latch 59 in the lever prevents accidental inward movement of the button 64.

Having fully described my invention, what I claim as new and desire to secure by Letters Patent, is:

1. The combination with the shaft of a window

panel actuating mechanism of the class described and a door latch operating rod, of a crank having a cup-shaped hub portion, a socket within said hub portion keyed to said shaft, means for retaining the hub portion against displacement from the shaft, a button unit keyed to and slidably engaging said hub portion, said unit having a cup-shaped button at its outer end for telescoping engagement with the socket of said hub portion in the movement of the button into the hub portion, means on the button unit cooperating with the hub limiting outward movement of said unit, means movable radially in the hub portion cooperating with said button unit to retain said unit against inward movement in the hub portion, and means for manually moving said last named means into inoperative position.

2. The combination with the shaft of a window panel actuating mechanism of the class described and a door latch operating rod, of a crank having a cup-shaped hub portion, a socket within said

hub portion keyed to said shaft, means for retaining the hub portion against displacement from the shaft, a button unit keyed to and slidably engaging said hub portion, said unit having a cup-shaped button at its outer end for telescoping engagement with the socket of said hub portion in the movement of the button into the hub portion, means on the button unit cooperating with the hub limiting outward movement of said unit, means movable radially in the hub portion cooperating with said button unit to retain said unit against inward movement in the hub portion, means for manually moving said last named means into inoperative position, a lever in operative engagement with said button unit and said latch operating rod, said crank comprising a handle member extending radially from said hub portion, and said last named means being disposed within the boundaries of the handle member adjacent the hub portion.

LOUIS J. GOUIN.
